UNITED STATES PATENT OFFICE.

FREDERICK BAKER, OF BLACKHEATH, LONDON, ENGLAND, ASSIGNOR TO SINGLE THREAD LOCKSTITCH MACHINES LIMITED, OF LONDON, ENGLAND, A COMPANY OF GREAT BRITAIN.

SEWING.

Original application filed January 17, 1923; Serial No. 613,223. Divided and this application filed January 25, 1924. Serial No. 688,571.

To all whom it may concern:

Be it known that I, FREDERICK BAKER, a subject of the King of Great Britain, residing at 42 Lee Road, Blackheath, London, 5 England, have invented new and useful Improvements in and Relating to Sewing, of which the following is a specification.

This invention relates to sewing and has for its chief object to provide a novel method 10 of manipulating a thread whereby novel forms of single thread locked stitching can be produced. Novel mechanism for this purpose is described in my co-pending application Serial No. 613,223, filed January 15 17th, 1923, of which this is a divisional application.

According to the present invention I produce single thread stitching which cannot be unravelled and is stronger than the ordinary 20 double thread lock stitch with a given size of thread.

The novel stitch can be formed in various ways, but in all cases the loop formed from the needle is formed into two loops, a small 25 or permanent loop and a large loop, the large or temporary loop being twisted and passed (i. e., noosed) over the small loop and being then drawn tight round it and so tied to it close under or within the work. 30 In the preferred construction hereinafter described this tying of the small loop is thus completed before the needle next pierces the material being sewn. Further features of importance in the preferred method of 35 forming my novel stitching reside in the fact that a portion of one of the strands of each needle loop is diverted and retained while the remainder of the loop is drawn out twisted and made to encircle the re-

40 tained portion in such a manner that on the completion of the stitch the said retained portion becomes a locked loop the length of which has been automatically determined by the feed or movement of the 45 material being sewn. This loop is in fact the smaller of the two loops into which each needle loop is formed as above stated.

In the preferred method of forming the 50 stitches the above mentioned diverted and retained strand of the needle loop involved in the second and all subsequent stitches of a line of sewing is carried through the previous loop and thereby itself becomes a loop extending through the bight of the said 55 previous loop.

A feature of the stitching in its preferred and finished form resides in the fact that the strands of the loops constituting the line of sewing on the underside of the material are twisted bodily around one another 60 thereby bringing them very closely in contact and giving a narrow appearance similar to the single thread extending along the underside of the material in ordinary lock stitching. 65

In order that the invention may be clearly understood and readily carried into effect the same will now be described more fully with reference to the accompanying drawings in which the manipulation of the needle 70 thread is illustrated, it being understood that there are many instances of distortion, enlargement and lack of right proportion in these drawings, particularly in showing the manipulation of the thread, in order to 75 render the same more clear and readily understood.

Figures 1 to 6 illustrate diagrammatically various stages in the manipulation of the thread for producing sewing in accordance 80 with my invention.

Figures 7 and 8 illustrate in plan view on the underside of the material and in perspective the resultant seam, magnified distorted and loosened for convenience of illustration. 85

Figures 9, 10, 11 and 12 represent modified manipulation of the thread in accordance with the invention.

Referring first to the manipulation of the 90 thread in accordance with Figures 1 to 6 it is seen by reference to these figures that as a needle thread loop A consisting of the strands a^1 and a^2 is being drawn out below the needle plate as shown in Figure 1 the strand a^1 is formed with a twist or incipient loop B as shown in Figure 2 and as the loop A continues to be drawn out it is twisted so that the position of the back and front strands is reversed as shown in Figure 3 95 and meanwhile the loop B is drawn back through the bight of a loop C. At this stage the usual feed mechanism of the machine operates and the material and thread shift to the left as shown in Figure 4. As the loop A is drawn up it is passed (i. e., noosed) 100 over the loop B as shown in Figure 5 and the tightening of the thread by the usual take-up mechanism causes the actual bight or bend of the loop A to slip around the strands of 105 110

the loop B as shown in Figures 6, 7 and 8. During the final tightening of the thread the encircled strands of the loop B and the strands of the loop C are twisted or turned 5 over upon themselves thereby producing a strong and firmly locked stitch and a close appearance of the double strands lying close against the material between the penetrations.

10. Although as hereinbefore stated my novel form of stitching in all cases involves the formation of a small loop and a large loop from a single needle loop and the passing of the temporary large loop over 15 the small permanent loop and drawing it up thereon, the actual formation and manipulation of these loops may be effected in various ways.

For example if the mechanism employed 20 engages a strand of the needle thread at a point above the bight of the retained loop penetrated by the needle the subsequent formation of the loops is as shown at two stages diagrammatically in Figures 9 and 25 10. If on the other hand the mechanism engages a strand of the needle thread at a point below the bight of the retained loop the subsequent formation of the loop is as shewn at two stages diagrammatically in 30 Figures 11 and 12.

The actual forms of the completed 35 stitches in these instances differ slightly but the more general characteristics already referred to are common to all.

35. What I claim is:—

1. A method of forming a single thread locked stitch consisting in drawing a single loop through each needle penetration of the material being sewn, dividing each such 40 loop drawn from the needle into two loops, a permanent loop and a temporary loop, twisting the temporary loop and passing it completely over the permanent loop in drawing up the said temporary loop to the 45 material being sewn.

2. A method of forming a single thread locked stitch consisting in dividing each loop drawn from the needle into two loops, a permanent loop and a temporary loop, 50 twisting the temporary loop, drawing the permanent loop through the bight of the permanent loop of the preceding stitching cycle, and passing the temporary twisted 55 loop completely over the permanent loop in drawing up the temporary loop to the material being sewn.

3. A method of forming a single thread locked stitch consisting in diverting a portion of one of the strands of each loop drawn from the needle and retaining it 60 while the remainder of the loop is twisted, made to encircle the retained portion and drawn up by the take-up until it becomes locked to the said retained portion at the end remote from the bight of the latter 65 whereby the latter becomes a locked loop of definite length.

4. A method of forming a single thread locked stitch consisting in diverting a portion of one of the strands of each loop drawn from the needle drawing said 70 diverted portion through the bight of the previously diverted portion of the loop of the preceding stitching cycle, and retaining it 75 while the remainder of the loop is twisted and made to encircle the retained portion and drawn up by the take-up until it becomes locked to the said retained portion at the end remote from the bight of the latter whereby the latter becomes a locked 80 loop of definite length.

5. A method of forming a single thread locked stitch consisting in drawing out a loop of thread from the needle, diverting a portion of one of the strands of said loop 85 and retaining it, twisting another portion of the loop and drawing it up to the material around and over the retained strand portion.

6. A method of forming a single thread locked stitch consisting in drawing out a loop of thread from the needle, engaging 90 a portion of one of the strands and drawing it as a loop through the bight of the previously engaged portion of the loop of the preceding stitching cycle, twisting the first mentioned loop and drawing it up 95 around and over the retained strand portion.

7. A method of forming a single thread locked stitch consisting in drawing a single loop through each needle penetration of the material being sewn, dividing each such loop into two loops, a permanent loop and a temporary loop, twisting and drawing the 105 permanent loop through the bight of the permanent loop of the preceding stitching cycle, and twisting and passing the temporary loop completely over the permanent loop in drawing up the temporary loop to 110 the material.

FREDERICK BAKER.
